DESIGN FOR A WALL BRACKET FOR FLOWERPOTS

Charles Kiss, Hamden, Conn.

Application October 31, 1938, Serial No. 80,790

Term of patent 7 years

To all whom it may concern:

Be it known that I, Charles Kiss, a citizen of the United States, residing at Hamden, in the county of New Haven and State of Connecticut, have invented a new, original, and ornamental Design for a Wall Bracket for Flower Pots, of which the following is a specification, reference being had to the accompanying drawing, forming part thereof.

Fig. 1 is a perspective view of a wall bracket for flowerpots showing my new design;

Fig. 2 is a front view of the same; and
Fig. 3 is a top plan view thereof.

The design is characterized by a relatively large, horizontally-arranged open loop with ends extending sidewise and terminating in loops of smaller size than the central loop.

I claim:

The ornamental design for a wall bracket for flowerpots, substantially as shown and described.

CHARLES KISS.
